Philip Lawrence Kennedy

UNITED STATES PATENT OFFICE.

DAVID A. DECROW, OF BUFFALO, NEW YORK, ASSIGNOR TO WORTHINGTON PUMP AND MACHINERY CORPORATION, A CORPORATION OF VIRGINIA.

PUMP-VALVE.

1,379,173.

Specification of Letters Patent. Patented May 24, 1921.

Application filed April 3, 1918. Serial No. 226,502.

To all whom it may concern:

Be it known that I, DAVID A. DECROW, a citizen of the United States, residing at Buffalo, county of Erie, and State of New York, have invented certain new and useful Improvements in Pump-Valves, fully described and represented in the following specification and the accompanying drawings, forming a part of the same.

10 This invention relates to improvements in pump valves, the object being to provide a valve which shall be efficient and durable under operation at very high speeds.

15 The following specification describes and the accompanying drawing illustrates a valve constructed in accordance with the invention, it being understood that changes may be made in the form, construction and arrangement of the parts, without departing 20 from the invention, the form herein disclosed being a preferred embodiment thereof.

In the drawings:—

Figure 1 is a vertical sectional view through a valve constructed in accordance 25 with the invention.

Fig. 2 is a top plan view of the same; and

Fig. 3 is a horizontal sectional view with parts broken away.

30 Referring to the drawing, 10 represents a cylindrical valve casing threaded for attachment in the valve deck, as usual. A spider 11 carries the central hub 12 tapped and threaded to receive the cap stem 13. Above the threaded portion of the cap stem, 35 the latter preferably is inclined outwardly, as at 14, this portion terminating in a shoulder 15.

The casing 10 is provided with a seat, as at 16, and within this seat is mounted an 40 annular resilient sealing ring or valve seat 17, of rubber, or other suitable material. This ring 17, in the present embodiment, is held in place by the form of seat 16 which is tapered to form an annular ridge 18, but 45 the resilient seat 17 may be secured in any suitable manner. The inner periphery of the ring 17 is formed with a bevel face 19.

Carried by the valve stem is a second annular, resilient sealing ring or valve seat 50 20, which rests on the top of the hub 12, embraces the inclined portion 14 of the valve stem, and is held at the top by the shoulder 15 when the cap stem is screwed into the hub 12. The outer periphery of the ring 20 55 aligns with the outer surface of hub 12 and

is formed with a beveled top face 21 complementary to the beveled face of ring member 17.

Seating on the resilient rings or seats 17 and 20 is the annular valve 22. This valve 60 is formed preferably of light sheet metal, and preferably is dished in shape, its outer and inner flaring walls seating on the beveled faces 19 and 21, respectively.

The abutment or cap consists of spider 23 65 with shouldered skirt 24 which serves as a stop for the valve and as a guide for the valve spring 25, which seats at the top against the skirt shoulder 26. Provision is made for guiding the valve without interfering materially with the flow. In the present embodiment, the inner edge of the valve 22 is formed with a narrow collar 27, which slides on guide lugs or arms 28 projecting from the cap stem within skirt 24. 70 With this construction, a free flow of the fluid is secured from the inner edge of the valve through the abutment or cap between the arms of spider 23. 75

It will be understood, however, that the 80 invention is not to be limited to the construction or arrangement of abutment or cap shown, nor to the particular form of the valve proper, as the invention claimed may be embodied in various constructions. 85

The essential feature of the construction and invention is the resilient valve seat in combination with the light plate valve, preferably of sheet metal, by which very high pump speed is made practicable and great 90 valve durability secured, as compared with the usual form of construction having a metal seat and a valve or valve face made of resilient material.

What is claimed is:

1. An automatic or pressure operated 95 pump valve structure, comprising a resilient seat and a light plate valve seating thereon.

2. An automatic or pressure operated 100 pump valve structure, comprising resilient inner and outer seats having beveled seating faces, and a light annular dished plate valve seating on said beveled faces.

3. An automatic or pressure operated 105 pump valve structure, comprising resilient inner and outer seats having beveled seating faces, and a light annular dished sheet metal valve seating on said beveled faces.

4. An automatic or pressure operated 110

pump valve structure, comprising a metal valve seat with an outer annular resilient seating ring having an interior beveled face, an inner annular, resilient seating ring having an exterior beveled face, a light annular, dished, sheet metal valve seating on said beveled faces, an abutment or cap provided with openings for the passage of fluid

through the cap from the inner edge of the valve, a backing spring between the valve 10 and cap, and guiding arms on the cap for the inner edge of the valve.

In testimony whereof I have hereunto set my hand.

DAVID A. DECROW.
